UNITED STATES PATENT OFFICE

ERNEST THOMAS FISK, OF SYDNEY, NEW SOUTH WALES, AUSTRALIA

SOUND SUPPRESSING VENTILATOR FITMENT FOR WALL APERTURES

Application filed June 27, 1928, Serial No. 283,764, and in Australia July 27, 1927.

The object of this invention is to provide means for facilitating ventilation through apertures in walls of buildings and through window openings whilst limiting transmission of sound in the incoming air. The invention is susceptible of a variety of applications. It may, for instance, be used to admit ventilation through an open window while suppressing the transmission of street noises into an apartment. It may be fitted to an existing door or it may be utilized as an auxiliary door to permit ventilation but to impede transmission of sound vibrations through it when the main door hung in the same frame is left open. Or it may be utilized in a partition between two apartments to facilitate circulation of air between these apartments whilst impeding transmission of sound from one apartment to the other.

The invention comprises a cellular screen or panel having airways through it by which ventilating air-currents can pass, but in which sound waves in the air are absorbed, refracted, or deflected and are not transmitted with the ventilation air except in a substantially damped state.

In the accompanying drawings:—

Fig. 1 is a sectional perspective view of a ventilator built into a wall;

Fig. 2 is a fragmentary detail section of a ventilator similar to Fig. 1;

Fig. 3 is a fragmentary section of a modification of the ventilator; and

Figs. 4 and 5 are detail sectional views of further modifications.

In Figs. 1 and 2 the device is shown as a hollow box 15 having non-aligning perforations 16 through the inner and outer sides of it, and lined with felt or other sound deadening material 17. The energy of sound vibrations in the in-passing air is largely absorbed in the mid-chamber 14 and the air passes through the cellular passages 16 on the inner side of the panel in a sub-divided stream and with the sound vibrations abstracted or damped.

Observation of results obtained in the use of such sound chamber panels suggests that they facilitate or at any rate only negligibly retard air flow through them when

wind blows against their external sides. But vibratory or oscillatory conditions in the inpassing air are broken down or absorbed and dissipated particularly when the air passages or the mid cell are lined with 55 felt, soft rubber, or other non-sonorous material.

The functioning of the panels may be exalted so that they will more completely check noise transmission without too far limiting 60 freedom for circulation of ventilation by fitting one or more perforate septa across the mid cell, and also by disposing the perforations in the inner septum and the panel sides staggered or out of alignment either by displacing them laterally or by varying their direction.

The highest efficiency is attained when the surfaces with which the incoming air contacts, are constructed of or lined with felt 70 or other non-resonating material in which sound waves will be absorbed, but useful results are still attained with structures of metal, glass, artificial stoneware, or other hard material by reason of the disposition 75 of the surfaces to deflect, reflect, and baffle the air currents and to procure damping of sound vibrations.

Fig. 3 illustrates a form of the invention in which the inner and outer walls 18—19 of 80 a hollow box are perforated at 20 and a perforate septum 21 is fitted in the chamber 22. This view suggests a construction in stoneware or like material, unlined.

A screen of louvre type is efficient so long 85 as the intervening louvre slats are disposed so that they operate to break up the wave front, the air vibrations carried past them being broken down by absorption or deflection in chambers within the structure 90 through which air flow takes place. Such a screen is shown in Fig. 4, in which the encasement 23 is fitted with oppositely pitched louvres 24 in the respective sides of it. A septum 25 may be fitted in the chamber 26 95 between the frontal and rear side louvres. This septum may be a perforate sheet of non-sonorous material, or it may be a sheet of cloth or felt appropriately perforated.

Fig. 5 shows another modification in which 100

a perforate plate 30 forms one side of the panel, and louvres 31 the other side of it, the septum being formed by reversely pitched louvres 32.

5 What I claim as my invention and desire to secure by Letters Patent is:—

A sound damping ventilating screen having perforated sides including sound damping material forming the walls of the perforations, said screen having an air chamber 10 between the perforated sides, and a perforate septum in said chamber.

In testimony whereof I affix my signature.
ERNEST THOMAS FISK.
